CLAIM

I claim the ornamental design for an electrical rocker switch assembly, as shown and described.

DESCRIPTION

FIG. 1 is a top perspective view of an electrical rocker switch assembly showing my new design;

FIG. 2 is a front elevational view with the rear being a mirror image thereof;

FIG. 3 is a left hand side view thereof; and,

FIG. 4 is a right hand side view thereof.

The broken line showing of the environment is for illustrative purpose only and forms no part of the claimed design.
